UNITED STATES PATENT OFFICE.

EARL HORTER, OF NEW YORK, N. Y., ASSIGNOR TO THE J. B. WILLIAMS COMPANY, OF GLASTONBURY, CONNECTICUT, A CORPORATION OF CONNECTICUT.

DESIGN FOR A RECEPTACLE FOR TOILET COMPOUNDS.

No. 40,076.

Specification for Design.

Patented June 22, 1909.

Application filed February 18, 1909. Serial No. 478,741. Term of patent 14 years.

To all whom it may concern:

Be it known that I, EARL HORTER, a citizen of the United States, residing at New York, in the county of New York and State of New York, have invented a new, original, and ornamental Design for a Receptacle for Toilet Compounds, of which the following is a specification, reference being had to the accompanying drawing, forming part thereof.

Figure 1 is a front elevation of the receptacle. Fig. 2 is a side elevation.

The design resides in the surface orna-

mentation herein which consists of an arrangement of sprays or stems extending more or less in the same direction and bearing representations of the flower well known as the violet.

I claim—

The ornamental design for a receptacle for toilet compounds, as shown and described.

EARL HORTER.
